UNITED STATES PATENT OFFICE.

JOHN T. LANCASTER, OF HAVERHILL, MASSACHUSETTS, ASSIGNOR TO HAMEL SHOE MACHINERY COMPANY, A CORPORATION OF MASSACHUSETTS.

HEEL-NAILING MACHINE.

1,395,838.

Specification of Letters Patent.

Patented Nov. 1, 1921.

Application filed May 6, 1918. Serial No. 232,689.

To all whom it may concern:

Be it known that I, JOHN T. LANCASTER, a citizen of the United States, residing at Haverhill, in the county of Essex and State 5 of Massachusetts, have invented certain new and useful Improvements in Heel-Nailing Machines, of which the following is a specification, reference being had therein to the accompanying drawings.

10 This invention relates to certain improvements in heel nailing machines and particularly those of that type disclosed in the patent to Pettengill, 1,119,763, December 1, 1914, in which a heel is pricked on a holder 15 in the rear of the jack simultaneously with the spanking of a top lift onto the heel of a shoe supported upon the jack, the pricked heel being nailed to a shoe by a subsequent operation of the machine. Machines of the 20 above type comprise a reciprocating cross head having mounted thereon a turret for supporting the nailing and spanking devices, the turret being oscillatable to permit the proper presentation of the nailing and 25 spanking devices in succession for carrying out the required sequence of operations. The machine is also provided with an awl carrier slidably mounted upon the cross head and arranged to be locked thereto for 30 performing the pricking operation and to be unlocked therefrom and held in raised position while the nails are being driven.

35 The machine of the patent above referred to, while provided with means for positively locking the turret in either the nail driving or spanking positions, requires that the operator unlock and turn the turret as a manual operation between the successive nailing and spanking strokes of the cross 40 head. The present invention therefore comprises the provision of automatically operating devices, serving to unlock the turret, to turn and to thereafter lock the same in its new position, such devices normally operating in the first half of each downward stroke 45 of the cross head.

As it is sometimes desirable, however, to repeat the operation of one of the devices carried by the turret, as for example the top 50 lift spanker, without the normal intervening operation of the other devices, the invention contemplates the provision of manually controlled means whereby the above described automatic turret turning devices are

rendered inoperative during one or more 55 successive strokes of the cross head.

In the machine of the above patent the awl carrier is positively locked to the cross head by a slidable bolt during the pricking operation, but is unlocked therefrom in the 60 interval between said operations. In said patent, means comprising a spring-pressed ball is provided for locking the awl carrier to the nail-plate slide holder during the intervals between said pricking operations, it 65 being necessary in view of the non-positive action of said ball, to provide additional means to insure the proper position of the awl carrier for engagement of the bolt therewith preparatory to the next pricking 70 stroke of the cross head.

This invention thus further consists in means comprising a spring-pressed bolt adapted to form a positive lock between the awl carrier and nail-plate slide holder, said 75 bolt being automatically retracted to unlocking position upon locking movement of the bolt which locks the awl carrier to the cross head, and being automatically restored to engaging position upon disengagement of 80 said latter bolt.

The invention further comprises additional and desirable details of construction all of which will be hereinafter more fully described and claimed, reference being had 85 to the accompanying drawings for a full disclosure of the same and in which,—

Figure 1 is a front elevation of so much only of the upper portion of a heel nailing machine as is necessary to illustrate the application of this invention thereto, the parts being shown in the position which they occupy just subsequent to the spanking operation, the cross head being in uppermost position,

90 Fig. 2 is a front elevation, partly in section, showing the mechanism at the left of Fig. 1, the cross head having moved slightly downward on its nailing stroke.

Fig. 3 is a view similar to Fig. 2, the cross 100 head, however, having moved to its lowermost position on the nailing stroke.

Fig. 4, is a view similar to Fig. 1, the parts, however, being shown in the position which they occupy just subsequent to the 105 nailing operation, the cross head being in uppermost position,

Fig. 5 is a front elevation, partly in sec-

tion, showing the mechanism at the left of Fig. 4, the cross head having moved slightly downward on its spanning stroke,

Fig. 6 is a view similar to Fig. 5, the cross 5 head having moved downward to its lowermost position at the end of the spanning stroke,

Fig. 7 is a perspective view of a bolt forming a part of the turret turning mechanism,

Fig. 8 is a sectional detail illustrating means for operating said bolt,

Figs. 9 and 9^a are detail views of a manually actuated controlling device for said 15 bolt,

Fig. 10 is a sectional detail of the latch for locking the turret, and the means for projecting the same,

Fig. 11 is a perspective of said locking 20 latch,

Fig. 12 is a partial top plan view showing the turret with its bolt actuating cam and the relative arrangement of the cross head, awl carrier and nail-plate slide 25 holder,

Fig. 13 is a sectional elevation central of the bolts for locking the awl carrier to the nail-plate slide holder and the cross head, respectively, and

Fig. 14 is a sectional detail of a portion of 30 the turret turning mechanism.

1 indicates a portion of the fixed frame of the machine having formed therein at 2 a guide member serving to slidably guide 35 a rod 3, said rod being connected to and supporting at its upper end, the reciprocable cross head 5, it being understood that the rod 3 together with its guide member is duplicated at the right hand side of the machine, not herein shown. The lower ends of the rods 3 are connected to a lower cross head suitably guided in the base of the machine, and which cross head is given a reciprocating motion by means of a crank and 40 connecting rod operated from any suitable source of power, all as clearly shown in the patent to Pettengill above referred to.

The cross head 5, at its central portion comprises front and rear plates 6 and 6^a, 50 such plates being spaced apart and having rotatably supported between them the turret 8. As herein shown the turret is fixed to a shaft 7, having journal bearings in said front and rear plates, the turret being provided with divergent arms 9 and 10 serving to support, at their outer extremities, a top-lift holder 11 and a nail driver holder 12, respectively. A suitable handle 13 may be fixed to one of the arms of the turret for 55 permitting manual turning of the same when desired.

Fixed to the forward end of the shaft 7 and in front of plate 6 is a sector 14, said sector having notches 15 and 16 formed in 60 its edge, and being also provided with a

crank arm 17. The sector is also furnished, at points substantially equidistant from the notches 15, 16, with outstanding lugs 18, 19, for a purpose to be hereinafter described.

20 is a boss projecting from the forward 70 face of the plate 6 adjacent said sector and having formed therein a guideway for a slide-

able latch member 21 (see Figs. 10 and 11), the right hand extremity of said latch member being reduced as at 22 for ready engage-

ment with the notches 15 and 16 of the sector 14. 23 is a cover plate secured as by

means of bolts 24 to the outer face of the boss 20, thereby serving to retain the latch 21 in proper operative position. Within said cover 80

plate at 25 is formed a longitudinal bore in which is located a compression spring 26, said compression spring being adapted to

engage at one end against a pin 27 projecting forwardly from the latch 21, and having 85

engagement at its opposite extremity with a screw 28 adjustable within a threaded portion of said bore 25, a slot 29 being formed

within said cover plate to accommodate the pin 27, which is slideable therein. From the 90

above construction, it will be evident that the latch 21 is constantly urged into engage-

ment relation to one or the other of said 95 notches 15, 16 of the sector 14, and that the tension of the spring which acts to project said latch may be varied at will by adjust-

ment of the screw 28. The boss 20 is pro- 100

vided adjacent the sector 14 with upper and lower hardened contact plates 18^a, 19^a 105

adapted to receive the impact of adjustable stop belts 18^b, 19^b, respectively, said bolts

serving to adjustably limit the arc of swing- 110

ing movement of said sector.

At its left hand extremity the latch 21 is 115

provided with an extension 30, having upon its rear face a block 31. The upper and lower surfaces of block 31 are inclined as at

32, 33 to form cams, the right hand extremities of said cams being connected by a sub- 120

stantially vertical surface 31^a, the purpose of which construction will be hereinafter 125

made evident. 34 is a bracket fixed to the frame member 1 and providing a support for a fixed upwardly extending rod 35, said 130

rod being guided near its upper extremity by passing through an opening formed in a bracket 36 depending from the cross head

5. At the upper end of the rod 35, is pivoted, as by means of pin 37, a block 38, said 135

block having rotatably mounted at its upper end an anti-friction roller 39 arranged for contact with the cam surfaces 32 and 33. The block 38 is provided upon its right hand 140

face with a lug 40 adapted to engage the vertical left hand surface of the boss 20, 145

serving thereby to guide said block during a portion of the downward movement of the cross head. A flat spring 41, carried by the 150

upper end of the rod 35, bears against the block 38 upon its left hand face adjacent

155

the roll 39 and acts to restore the block 38 to vertical position if the same be turned in a counter-clockwise direction about its pivot.

Consideration of the structure thus far described will show that upon downward movement of the cross head, carrying with it the turret 8 and latch 21, the roll 39 which lies in the downward path of movement of the cam 32 will contact with the latter and as the block 38 is prevented from swinging movement to the right about its pivot by engagement of lug 40 with the boss 20, the cam member 32 in moving over said roll 39 will cause a sliding movement 10 of latch 21 to the left, thus serving to disengage said latch from either of the notches 15, 16 with which it may have been engaged. As the cross head continues to move down, roll 39 passes up the vertical surface 31^a of 20 the cam block 31 and finally becomes entirely disengaged from said block, the latch 21 now being free to return under action of spring 26 into engagement with either of the notches 15 or 16 which may be in position 25 to receive it. Upon upward movement of the cross head, the roll 39 being engaged by the cam 33, will swing block 38 about its pivot 37 against action of spring 41 without causing any movement of the latch 21, the 30 roll thus being restored to its initial position below block 31.

Pivoted at the point 42 upon the cross head is a bell crank lever 43, said lever being provided with arms 44, 45 and 46. 47 is a 35 crank pin projecting forwardly from the crank arm 17 of the sector 14, and being connected to the arm 44 of the bell crank 43 by means of a link rod 48. 49 is a bracket extending outwardly from the face of the 40 cover plate 23, and provided with a guide opening through which passes the link 48. Surrounding said link 48 is a coil spring 50, said spring bearing at one end against the bracket 49 and at its opposite end against a 45 nut 51 adjustably threaded upon the link 48, whereby the tension of said spring may be varied.

52 is a vertically slidable rod guided within suitable openings in brackets 34 and 36, 50 the lower end of said rod being provided with an extension 53 slidable in an axial bore in said rod and normally held in projected position by a relatively heavy spring, a pin 54 slidable in a slot 55 in said rod 52 serving 55 to retain the extension 53 in proper relation to said rod 52. Formed in the bracket 34 is a transverse guide opening 56 within which is slidably mounted a bolt 57 (see Figs. 7 and 8), the right hand extremity 58 of said 60 bolt being normally projected across the path of the lower end of said rod 52 by means of a spring 59 located within a chamber 60 in said bolt 57, said spring bearing at one extremity against the inner wall 61 of said chamber, and at its

opposite extremity against a pin 62 fixed in the bracket 34. The bolt 57 is provided at 62^a with a slot having at 63 an inclined surface forming a cam, said cam being arranged for engagement with a complementary cam incline 64, formed upon a slidable cam member 65. Cam member 65 is slidable within suitable guides 66 formed within the bracket 34 and is arranged to move transversely of the path of bolt 57, and 70 to lie within slot 62^a thereof. A cover plate 67 is provided for retaining said bolt 57 and cam member 65 in proper relative position within said guides. 75

The cam member 65 is formed with a bore 80 68 passing entirely through the same from end to end, and freely movable within said bore is a rod 69, said rod having at its lower extremity a head 70 engageable with the lower end of the cam member 65. The upper 85 end of the rod 69 has pivotally connected thereto at the point 71 a link member 72, the latter being pivoted at its opposite extremity 73 to the arm 46 of bell crank lever 43. The upper end of the slidable rod 52 is 90 connected by means of a suitable link 74 with the arm 45 of said bell crank lever 43. Adjustably secured to the rod 69 near its upper extremity is a stop member 75, said stop member being arranged to engage the 95 upper end 76 of cam member 65 upon downward movement of said rod 69.

The bolt 57 at the point 77 is provided with an opening for the reception of a pin 78 forming a pivotal support for a manually operable lever member 79, said lever member being provided at 80 with a cam surface arranged for engagement with the left hand face 81 of the bracket member 34. 100

In the machine as herein shown 85 is the nail-plate, 86 the nail-plate slide, 87 the nail-plate slide holder, and 88 the awl carrier, all as shown in the above mentioned patent to Pettengill. As in the above mentioned patent, the present device is provided at 89 105 with a cam groove formed upon the turret between the front and rear plates of the cross head, said cam groove being arranged for operative engagement with an antifriction roll 90 carried by a bolt 91 slidably 110 guided within suitable openings 92, 93 in said cross head and having its rear extremity arranged for locking engagement with an opening 94 in the awl carrier, whereby said awl carrier may be locked to the cross 115 head for movement therewith.

The nail-plate slide holder 87 is provided at 95 with an opening, within which is fixed the sleeve member 96 extending outwardly from a bolt housing 97, said housing being 120 provided at 98 with a bore adapted to guide the stem portion of the bolt 99, the head of which is slidable within and guided by the sleeve member 96. 100 is a compression spring seated within the bore 98 of member 125 130

97 and passing within a pocket formed in the stem of bolt 99, said spring tending normally to project said bolt toward the free extremity of said sleeve member 96. The 5 rearward portion of opening 94 in awl carrier 88 is of greater diameter than the forward part thereof, being of substantially the same size as is the opening 95 in nail-plate slide holder 87, and has fixed therein 10 a hardened bushing 101, the internal diameter of which is the same as that of the sleeve member 96. The bolt 99 is formed with an enlarged head having a cylindrical portion 102 slidable within the sleeve member 96, as above described, and being also 15 slidable within the bushing 101, the outer extremity of said bolt head being conical as shown at 103, having its apex in axial alignment with opening 94.

20 The operation of the above described mechanism is as follows, the parts being considered as in the initial position shown in Fig. 1, in which the cross head has just reached its uppermost position after performing the top-lift spanking stroke, it being noted at this time that the cam member 65 is up in such position as to permit the bolt 57 to be projected by its spring into the path of the rod 52, the latter, however, being elevated out of contact with said bolt.

As the cross head moves downward, the roll 39 immediately comes into contact with the cam 32 and causes a retraction of the latch 35 21, said latch being wholly retracted as shown in Fig. 2, substantially at the instant of contact of the lower extremity of the rod 52 with the top of the bolt 57, the slidible extension 53 of said rod 52, however, providing for slight inaccuracies of the timing of these parts. Immediately upon contact of the lower extremity of rod 52 with said bolt, further downward movement of said rod 52 is prevented, thereby causing a turning 45 movement of bell crank lever 43 about its pivot 42 as the cross head moves downward, thus, through the link 48, acting to turn the sector 14 and therewith the turret 8, at the same time compressing the spring 50 55 between the bracket 49 and the nut 51.

As the turret thus turns to bring the nail driver element 12 into operative position, the bolt 91, which has previously locked the awl carrier 88 to the cross head 5, is retracted, 55 thus freeing the awl carrier from the cross head, the bolt 99, however, at this time moving forwardly under action of spring 100 until the cylindrical portion 102 of its head comes into engagement with the bushing 101, 60 thereby positively locking the awl carrier to the nail-plate slide holder 87. As the downward movement of the cross head continues the turret will be turned until the latch 21 is opposite the notch 15, the roller 39 having 65 at this time passed up by the cam-carrying

block 31, latch 21 thus being free to move to the right under action of its spring 26 into latching engagement with said notch 15. The above movements all take place during the first half of the downward movement of the cross head, thus locking the turret in position with the nail drivers 12 in operative position for driving the nails, which operation takes place during the latter portion of the downward movement of the 75 cross head.

During the latter portion of such movement, the stop member 75 contacts with the upper end of the cam member 65, and thereby positively moves the same downwardly, 80 thus through engagement of the cam elements 64 and 63 retracting the latch 56 from below the lower extremity of the rod 52, thereby permitting slight further downward movement of the latter into the position 85 shown in Fig. 3, said figure indicating the position of the parts at the end of the downward movement of the cross head for driving the nails, it being noted at this time that the members 46 and 72, which together constitute a toggle connection are in alinement, and that the spring 50 is held under compression by engagement of the latch 21 with the notch 15.

As the cross head now rises from the lower 95 limit of its movement the parts assume the positions shown in Fig. 4. By reason, however, of the straightening of the toggle connection between the bell crank 43 and the rod 69, the nut 70 upon the lower extremity 100 of the latter is not raised high enough at this time to lift the cam member 65 to such an extent as to permit projection of the bolt 57 into the path of the slide member 52.

As the cross head now moves downwardly 105 from the position shown in Fig. 4 to perform the top lift spanking stroke, the roll 39 again contacts with the cam 32 and retracts the latch 21 from the notch 15. As the spring 50 is under compression and as 110 the member 52 is now free for downward movement, the immediate effect of such release of latch 21 from notch 15 is to cause a turning movement of the turret, sufficient to bring the spanker block 11 into operative 115 position. This turning movement of the turret serves simultaneously to move the bolt 91 into operative engagement with the opening 94 of the awl carrier, the latter having been positively retained in fixed relation to 120 nail-plate slide holder 87 during the nail-driving movement of the cross head by engagement of cylindrical portion 102 of the bolt head with the bushing 101 as above described.

Immediately upon contact of the rear extremity of bolt 91 with the conical portion 103 of bolt 99, said bolt is moved backwardly against its spring 100 until the cylindrical portion 102 of its head is removed 130

from contact with said bushing 101. The provision of the conical portion 103 of said bolt head makes it unnecessary to move the bolt 91 through the whole thickness of the 5 awl carrier 88 in order to fully retract bolt 99 therefrom, as any downward movement of the awl carrier relatively to the nail-plate slide holder 87, after such disengagement of the cylindrical portion 102 of the 10 bolt head, will, by engagement of the interior wall of bushing 101 with the conical portion 103 of the bolt, cam the same backward to cause a complete retraction of the bolt from the awl carrier, thus providing 15 for a rapid and positive unlocking of the awl carrier and nail-plate slide holder simultaneously with the locking of the awl carrier to the cross head.

As the cross head continues its downward motion, the stop member 75 again contacts with the top 76 of the cam member 65, moving the same down from its intermediate to its lowermost position, but without any effect upon the bolt 57, the latter 25 already being held in retracted position, the parts being arranged as shown in Fig. 6 at the end of the spanking movement of the cross head. The cross head now moves upwardly into the position shown in Fig. 1, it 30 being noted, however, that by reason of the breaking of the toggle connection between the bell crank 43 and the rod 69, the nut 70 during such upward movement of the cross head will contact with the lower extremity of the cam member 65 raising the same to such an extent as to permit bolt 35 57 to be moved into its projected position across the path of the member 52 by actuation of the spring 59, thus restoring the 40 parts to initial position as shown in Fig. 1.

From the above description, it will be evident that upon alternate downward movements of the cross head the turret will be swung into nail-driving and spanking positions and will be locked during substantially the whole time between actuations. As in certain cases it is desirable to perform two spanking movements in succession, it is necessary to provide for intermitting such alternate operations under such circumstances, and for this purpose the lever member 79 45 has been provided. As will be seen from inspection of Fig. 9, said lever 79, when raised into the horizontal dotted line position, will, by reason of engagement of its cam 80 with the face 81 of the bracket 34, cause a retracting movement of the bolt 57 regardless of the position of the cam member 65, such retracting movement, however, not 50 being to the full extent provided by the engagement of cam surfaces 64 and 63, but being sufficient to remove the bolt from the path of the rod 52. If now the operator desires to cause two spanking movements of 55 the cross head in succession, he will immedi-

ately after the first of such movements turn said lever 79 into horizontal position, where it will be temporarily retained by frictional engagement of the cam 80 with surface 81, thereby retracting said bolt and permitting 70 the machine to perform a second sequence of operations similar to that shown in Figs. 4, 5 and 6. As is clear, however, from Figs. 3 and 6, the final downward movement of the cross head always serves to move the cam 75 member 65 to its downward limit of movement, thereby fully retracting the bolt 57. The retraction of said bolt is sufficient to cause disengagement of the cam 80 from the surface 81, the weight of the lever 79 then 80 acting to restore the latter to vertical position, the machine thus, on the next downward movement of the cross head, being free to take up its alternate series of operations.

From the above description, of the mechanism and its mode of operation, it will be evident that the present invention provides automatic means for turning the turret from one to the other of its operative positions, 90 thus relieving the operator of the necessity of turning the turret between each successive operation and enabling him to devote his entire attention to the proper positioning of the shoe with respect to the nail-driving elements, such means, however, being controllable at the will of the operator whereby one of such operations may be repeated indefinitely, if desired.

It will also be noted that by the employment of the above described mechanism for locking the awl carrier to the nail-plate slide holder much of the uncertainty of operation of prior machines has been avoided, as well as the complication of structure 100 found necessary in such machines in attempting to avoid such uncertainty in operation, the present mechanism providing a simple and efficient device which is positively operative under all circumstances for 105 holding the awl carrier in proper retracted position during the nailing operation, but which is automatically and positively unlocked simultaneously with the locking of the awl carrier to the cross head for the 110 pricking operation.

While the above described mechanism is a preferred embodiment of the invention, it is to be understood that the invention is not to be restricted to the specific details thereof, 115 but that various changes and modifications in the structure may be made such as fall within the scope of the appended claims.

Having thus now described the invention together with a specific embodiment of the same and the mode of operation thereof what I claim and desire to secure by Letters Patent of the United States is,

1. In a heel nailing machine, in combination, an oscillatable turret, mechanism con-

structed and arranged automatically to swing said turret from one operative position to another, and means under control of the operator for intermitting the operation 5 of said mechanism while the machine is in operation.

2. In a heel nailing machine, in combination, an oscillatable turret provided with heel nailing and spanking devices, automatically actuated means for turning said 10 turret alternately to nailing and spanking position, and means locking said turret in either of said positions during substantially the entire interval between the turns of said 15 turret.

3. In a heel nailing machine employing a turret having nailing and spanking devices carried thereby, in combination positively actuated mechanism for turning said turret 20 to position for operation of one of said devices and resilient means for turning said turret to position for operation of the other of said devices.

4. In a heel nailing machine having a 25 reciprocable cross head and an oscillatable turret carried thereby, a locking latch arranged to hold said turret in fixed position when said cross head is stationary, means acting automatically upon movement of the 30 cross head for retracting said latch to release the turret, and automatically actuated mechanism for oscillating said turret.

5. In a heel nailing machine having a reciprocable cross head and an oscillatable 35 turret mounted thereon, means for oscillating said turret and means for locking said turret in either of two operative positions, said locking means comprising a latch, a spring for advancing said latch, and automatically actuated cam means for retracting 40 said latch.

6. In a heel nailing machine having a reciprocable cross head and a turret carried thereby, in combination, means actuated 45 upon movement of the cross head for turning said turret, a latch for locking said turret in either of two positions, spring means for advancing said latch, and cam means for retracting said latch, said means 50 comprising a cam element and a roller for engaging the same, one of said engaging parts being carried by the latch and the other being relatively fixed with respect to the movement of the cross head.

55 7. In a locking device for the oscillating turret of a heel nailing machine of the type employing a reciprocating cross head, a latch adapted to have locking engagement with the turret in either of two positions 60 of the latter, a cam carried by the latch, and a roller for engaging said cam and mounted upon a fixed part of the machine.

8. In a heel nailing machine having a reciprocatory cross head and an oscillatable 65 turret carried thereby, in combination, a

locking latch for holding said turret in operative position, a spring for advancing said latch for locking engagement with the turret, a cam member mounted upon the latch and a pivotally supported cam engaging roller mounted upon a fixed part of the machine frame, said roller being constructed and arranged to operatively engage said cam to retract the latch upon downward movement of the cross head, and to be 70 swung out of operative engagement with said cam upon upward movement of the cross head.

9. In a heel nailing machine having a reciprocable cross head and a turret mounted 80 thereon, means for turning said turret comprising a slidable rod, and a retractable bolt normally projected across the path of said rod for limiting the sliding movement thereof.

10. In a heel nailing machine having a reciprocable cross head and a turret oscillatable thereon, means for oscillating said 90 turret comprising a rod vertically slidable in fixed bearings, a stop member movable into the path of said rod to limit the movement of the same and means for automatically moving said stop member into and out of the path of said rod upon alternate reciprocations of the cross head.

95 11. In a heel nailing machine having a reciprocable cross head and an oscillatable turret carried thereby, in combination, means for oscillating said turret comprising a crank arm carried thereby, a ball crank lever pivoted to the cross head, a link connecting the crank arm and one arm of the bell crank lever, a vertically slidable rod connected to the other arm of said lever, and means for limiting the sliding movement of said rod, whereby downward reciprocation of the cross head serves to swing said bell crank and thereby to turn the turret.

110 12. In a heel nailing machine having a reciprocable cross head and a turret carried thereby, in combination, means for turning said turret comprising a slidable rod, a slidable bolt, spring means for projecting said bolt transversely across the path of 115 said rod, means normally operative upon alternate reciprocations of the cross head to retract said bolt out of the path of said rod, and manually operable means for retracting said bolt at will.

120 13. In a machine of the class described having a reciprocable cross head and a turret oscillatable thereon, in combination, means for oscillating said turret comprising a bell crank lever mounted upon the 125 cross head and having connections with the turret, an element guided for movement upon the machine frame and connected to said bell crank lever, means movable across the path of said element for limiting the 130

- movement of the same, connections between said bell crank and said means for moving the latter into and out of the path of said element upon alternate reciprocations of 5 the cross head, and a manually operated device for moving said limiting means out of such path at will.
14. In a heel nailing machine, a turret turnable in opposite directions into either 10 nail driving or spanking position, in combination, means for turning said turret from one of said positions to the other comprising a resilient member having operative connection with the turret, means 15 for tensioning said resilient member and for holding the same under tension, and means for releasing said resilient member to thereby permit the same to turn the turret.
15. In a heel nailing machine having a reciprocable cross head and a turret oscillatable thereon, in combination, means for oscillating said turret comprising a crank arm fixed to said turret, a bell crank lever 25 pivoted to the cross head, a link rod connecting said arm and lever, a bracket fixed to the cross head and having a guiding opening for said link rod, an adjustable stop member carried by said rod and a coil 30 spring surrounding said rod and having its ends bearing against said bracket and said stop member respectively.
16. In a heel nailing machine a reciprocable cross head, a turret oscillatable thereon 35 and having fixed thereto a crank arm and a member providing a pair of latch engaging openings, a latch for engaging either of said openings, a bell-crank lever pivoted to the cross head, a link rod connecting said lever 40 and crank arm, a coil spring encircling said link rod and having engagement at opposite ends with a fixed abutment and a stop member on said link rod respectively, a slide rod pivotally connected to said bell 45 crank lever, fixed guiding means for said rod, a stop bolt slidable across and resiliently positioned in the path of said slide rod, and mechanism including a toggle connection and a slide cam member for retracting said bolt upon alternate reciprocations of the 50 cross head.
17. In a heel nailing machine having a reciprocable cross head and an awl carrier slidable thereon, positive means for locking 55 said awl carrier against movement with the cross head, and means for locking said awl carrier to the cross head for movement therewith, said first means being controlled in its action by operation of said second means.
18. In a heel nailing machine, in combination, a reciprocable cross head, a nail-plate slide holder and a slidable awl carrier, means for positively locking said awl carrier to the nail-plate slide holder, means for 60 positively locking said awl carrier to the cross head, and mechanism for automatically and alternately moving the respective locking means into locking position.
19. In a heel nailing machine having a reciprocable cross head and an awl carrier 65 slidable with respect thereto, a bolt for positively locking said awl carrier in inoperative position, and a second bolt for locking said awl carrier to the cross head, locking movement of said second bolt acting to move 70 said first bolt out of locking position.
20. In a heel nailing machine having a reciprocable cross head and a nail-plate slide holder, in combination, an awl carrier slidable 75 mounted between said head and holder, said awl carrier being provided with an opening therethrough, a bolt slidable in said nail-plate slide holder and arranged to be projected into locking engagement with said opening, a spring for projecting said bolt, and means for positively retracting said bolt.
21. In a heel nailing machine having a relatively fixed part and an awl carrier slidable with respect thereto and provided with a bolt-receiving opening, means for locking said awl carrier to said relatively fixed part, comprising a spring projected bolt, said bolt having a cylindrical head arranged to have locking engagement with said opening in the awl carrier, and a substantially conical end portion.
22. In a heel nailing machine having a nail-plate slide holder and an awl carrier slidable with respect thereto, in combination, means for normally locking said awl 90 carrier to said holder, comprising a spring-pressed bolt having a part arranged for positive locking engagement with said awl carrier, means for partially retracting said bolt to disengage said part from the awl 95 carrier, and means for completing the retraction of the bolt.
23. In a heel nailing machine having a reciprocable cross head and an oscillatable turret carried thereby, an awl carrier slidable with respect to the cross head, a spring-pressed bolt for locking said awl carrier in inoperative position, a second bolt for locking said awl carrier to the cross head 100 for actuation thereby, and cam means active 105 upon turning of the turret for moving said second bolt, movement of said latter bolt into locking position serving automatically to cause disengagement of said first bolt from the awl carrier.
24. In a heel nailing machine, in combination, a reciprocable cross head, a nail-plate slide holder and an awl carrier, said parts being arranged for relative sliding movement and each being provided with an opening, said openings being in alinement when the respective parts are in normal position, a spring-pressed bolt slidable in the opening 110 115 120 125

in the nail-plate slide holder and engageable within the opening in the awl carrier, a second bolt slideable in the opening in the cross head and engageable with the opening in the awl carrier, and means for projecting said second bolt into said latter opening, contact of said second bolt with the first

bolt serving to cause movement of the latter out of locking engagement with the awl carrier opening.

10

In testimony whereof, I have signed my name to this specification.

JOHN T. LANCASTER.
